UNITED STATES PATENT OFFICE.

FRANCIS A. BUSHEY AND FREDERICK G. HARCOURT, OF CAMAS, WASHINGTON.

HORSESHOE.

1,035,530.

Specification of Letters Patent. Patented Aug. 13, 1912.

Application filed May 24, 1911. Serial No. 629,112.

To all whom it may concern:

Be it known that we, FRANCIS A. BUSHEY and FREDERICK G. HARCOURT, citizens of the United States, residing at Camas, in the county of Clark and State of Washington, have invented certain new and useful Improvements in Horseshoes, of which the following is a specification, reference being had therein to the accompanying drawing.

10 This invention relates to horse shoes, and the principal object of the same is to provide a detachable calk which can be readily removed when it is desired to sharpen the same.

15 Another object of the invention is to provide the calk with an improved type of base whereby the calk may be securely clamped in place.

20 This invention is illustrated in the accompanying drawings, wherein:—

Figure 1 is a bottom plan view of the shoe. Fig. 2 is a section along the line 2—2, in Fig. 1. Fig. 3 is a section along the line 3—3, in Fig. 1. Fig. 4 is a section along the 25 line 4—4 in Fig. 1. Fig. 5 is an enlarged fragmentary view of the shoe. Fig. 6 is an enlarged perspective view of one of the heel calks.

25 This invention comprises a shoe 1 which may be formed of any suitable material and which is provided with a dovetail tapered seat 2 in the toe having an under-cut front wall 3. Each heel is also provided with a dovetail tapered seat 4 having an under-cut front wall so that the heel calks will be held 35 in place. The heels are each provided with aligned openings 5 and 6 formed through the side walls of the seat 4, the opening 5 being threaded and the opening 6 being unthreaded and provided with an enlarged outer portion. The toe portion of the shoe is 40 provided with transversely extending openings 7 and 8 which are formed in alignment and communicate with the seat 2, the outer portion of the opening 7 being enlarged.

45 The toe calk comprises a dovetail tapered base 9 which has a sloping front face and which is provided with a transverse opening 10 which registers with the openings 7 and 8 when the calks are in place. An enlarged 50 body portion 11 is formed integral with the base and extends beyond the front wall of

the base to such an extent that when the calk is in place the front face of the calk will be flush with the face of the shoe. A 55 bolt 12 passes through the openings 7 and 8 and through the opening 10 and prevents the calk from sliding longitudinally in the seat. The head of the bolt is seated in the enlarged end of the opening 7 so that the 60 head of the bolt will be counter-sunk and the bolt is held in place by means of the nut 13. From an inspection of Fig. 4 it will be seen that the forward portion of the base extends into the under-cut portion of the 65 seat so that the calk is better braced and prevented from dropping out if the bolt becomes broken.

70 The calks which are used in the heels each comprises a dovetail tapered base 14 which is provided with a transverse opening 15 which registers with the openings 5 and 6 so that a securing bolt 16 can be passed through the openings formed through the walls of the seat 4 and through the opening 75 15 to hold the calk in place. A nut 17 is threaded upon the outer end of the bolt 16 so that the bolt will be securely locked in place. The calk is provided with an enlarged outer portion which rests upon the 80 shoe and the base is provided with a sloping forward face so that the base can extend into the under-cut forward portion of the seat. It will thus be seen that the heel calks are both held in place by the same method. 85

What we claim as our invention is:—

90 A horse shoe having its toe portion cut to form a seat leading from the inner edge and having undercut side and front walls, a calk conforming to the contour of the toe portion of said shoe and having its front and rear faces flush with the outer and inner faces of the toe of said shoe, a dove tailed lug formed upon said calk and fitting into said seat, and securing means passing transversely through said lug and the toe of said 95 shoe to hold said calk in place.

In testimony whereof we hereunto affix our signatures in presence of two witnesses.

FRANCIS A. BUSHEY.

FREDERICK G. HARCOURT.
